X-RAY TUBE

Albert Bouwers, Eindhoven, Netherlands; vested
in the Alien Property CustodianApplication January 15, 1941, Serial No. 374,582
In the Netherlands October 6, 1939

7 Claims. (Cl. 250—90)

There are protected X-ray tubes which are arranged in an envelope filled with an insulating liquid. The insulating liquid used is generally transformer oil, but other liquids, as chlorine or fluorine containing hydrocarbons, also enter into consideration.

Such a liquid has the advantage that its use prevents the formation of air gaps between the wall of the envelope and those parts which are at high voltage potential, thereby obviating electrical disturbances in the apparatus. Consequently, the whole of the tube and the envelope may have smaller dimensions than if the insulating medium within the safety envelope consists entirely or partly of air. However, the use of an insulating liquid also entails disadvantages which are brought about by the development of heat in the X-ray tube when it is loaded.

In protected tubes having air-insulation the heat is mostly conducted to a metal body extending outside the tube and is subsequently given off to the shield by radiation and convection. The surface of this shield is of such size that it can easily give off the heat to the surrounding air and its temperature does not rise excessively.

When an insulating liquid is used the transfer of heat from the cooler to the envelope is principally effected by convection. This means that the liquid which makes contact with the cooler of the X-ray tube is heated and gives off heat to cooler parts of the apparatus with which it makes contact later. These parts may also include those for which heating may be harmful. Consequently, it may be necessary to take measures to prevent this.

This particularly applies to those cases in which the X-ray tube, together with other parts of the X-ray apparatus such as the transformer which supplies the high voltage to the tube, is arranged in a common housing filled with oil. If no special measures are taken, these parts are heated during operation of the apparatus by the energy which is transformed into heat in the X-ray tube. In such instances, the auxiliary apparatus instead of being cooled by the oil is on the contrary, heated by the oil.

Besides, the heating may lastly be harmful to the liquid itself. Consequently, a renewal is desirable from time to time and this is an unpleasant work which takes much time and cannot be easily carried out by the user himself. Another factor to be considered is that the minimum dimensions of the apparatus are also determined by the condition that a definite temperature of the oil may not be exceeded since for a given power input the localized temperatures within the apparatus increase as the heat dissipating surfaces are reduced.

According to the invention these drawbacks are obviated. For this purpose use is made of an X-ray tube in which the heat is not transferred to a cooler fastened to the anode and projecting from the tube but to the wall of the tube. This manner of heat transfer is described in U. S. Patent No. 2,228,384 dated January 14, 1941, and does not in itself constitute the invention.

10 The wall of the tube is preferably provided with a metal part surrounding the anode and care is taken that the anode has a good heat-radiating surface and is fastened in such manner that no appreciable conduction of heat to other parts than the metal part of the wall can occur.

15 According to the invention, a tube of the said type is connected to the metal wall of the housing, filled with an insulated liquid, in such heat-conductive manner that the heat is transferred directly to the housing, that is to say without any appreciable conduction by liquid.

20 X-ray apparatus are already known in which the X-ray tube and the high-tension transformer are arranged in a common housing filled with oil and in which the heat of the anode is carried off without the oil serving as conveying means, for example due to the cooler being led through the wall of the housing. In this case the tube is wholly surrounded by oil and insulated by this liquid from the metal housing connected to earth. Since the anode is connected to the housing, the cathode has to be insulated for the full working voltage of the housing. This precaution also applies to the terminal of the source of supply to which the cathode is connected and to the current-supply conductors. Because of this the advantage of a symmetrical arrangement has to be abandoned.

25 By conducting the heat according to the invention to the wall of the tube and "grounding" the latter not only electrically but also thermally a considerable saving in space and weight is obtained as compared with the known apparatus. In addition, in the device according to the invention it is only necessary to insulate for half 30 of the tube voltage since the tube may be symmetrically arranged relatively to the grounded envelope.

35 Also special apparatus are known in which an X-ray tube consisting for the greater part of metal forms one unit with the transformer and in which only an insulating part which carries the cathode extends into the oil. These apparatus also could not be generally used since in practice apparatus are preferred which are symmetrically arranged and in which the tube may be readily replaced.

40 In particular if the tube and the shield do not constitute one separate part of the X-ray tube but the housing, in addition to the X-ray

tube, also contains one or more other components, as condensers, transformers, or valves it is of importance that the tube can be easily removed from the remainder of the apparatus.

In order to facilitate in this case the replacement of the tube it may be fastened to the cover of the housing so that, together with this cover, it can be removed from the housing after the mechanical connection between the cover and the housing, which naturally must be liquid-tight, has been loosened.

In order to ensure proper conduction of heat from the tube wall to the housing the latter, or the cover of the housing, may be provided with a saddle-shaped part which serves to support the tube, and one or more metal clips may be provided which embrace the X-ray tube, clamping it against the saddle-shaped part. These metal clips serve in this case also for the conduction of heat.

The heat-conductive contact from the wall of the X-ray tube to the wall of the housing, the "thermal short-circuit," is further promoted by surrounding the tube with an envelope consisting of a soft substance of good heat-conductive material, for example lead. The largest possible contact-surface of the tube wall with the tube and the metal clips respectively is thus obtained. The soft material can be easily forced against the parts with which it is in contact, thus reducing interruptions in the contact surface to a minimum.

In the construction according to the invention the heat is carried away from the wall of the tube directly to the housing. There is no perceptible difference in temperature between the tube wall and the housing and, since the whole outer surface of the latter is available to transfer the heat to the surroundings, it undergoes a but slight heating.

Consequently, the insulating liquid serves exclusively as an insulator and does not act as means to carry off the heat from the tube. It consequently remains cool and thus retains its good properties for a much longer time. In X-ray apparatus the conversion of electrical energy into heat is principally effected by the X-ray tube. The losses in transformers and other components are but slight compared with the heat which is developed in the tube, and do not cause any harmful heating of the liquid.

Since the liquid does not serve as cooling means the volume of the device may be made smaller which facilitates portability and renders it possible for more parts to be combined with the X-ray tube into one movable unit.

In addition, an important advantage of the constant coolness of the oil is that the expansion, which is about 1% per 10° C., is much less than in the apparatus in which the oil is heated. With a suitable shape of the housing a slight curvature of the wall may bring about an increase of volume which suffices for the expansion of the liquid so that the usual expansion device can be omitted.

The invention will be explained more fully by reference to the accompanying drawing showing diagrammatically one example of a construction shown in two sections.

Fig. 1 is a longitudinal section and

Fig. 2 is a cross-section of an X-ray apparatus comprising an X-ray tube and a device for increasing the voltage. The X-ray tube, together with the other components of the apparatus, is

arranged in a common housing filled with an insulating liquid.

The wall of the X-ray tube 1 has a cylinder-shaped metal part surrounded by a layer of lead 2. Glass parts 3 and 4 of the wall of the tube are sealed to the edges of the metal part, each carrying an electrode of the tube.

The cylinder-shaped, lead-covered metal part of the wall of the tube fits into a depression of a metal body 5. Metal clips 6 and 7 embrace the X-ray tube, clamping it against the saddle-shaped part 5 so that a good heat conductive connection is obtained between the metal part of the tube wall and the body 5. The latter is fastened to a plate 21 which constitutes the cover of a metal tank 22 and seals the latter hermetically.

The tank 22 contains not only the X-ray tube but also two rectifying tubes 8 and 9, two condensers 10 and 11 and two heating-current transformers 12 and 13.

One electrode of the condenser 10 is connected to the anode 38 of the X-ray tube and to the cathode of the rectifying tube 8. The other electrode is connected to the cathode of the rectifying tube 8 and to a current-supply conductor 14.

One electrode of the condenser 11 is connected to the anode of the rectifying tube 9 and to the cathode 31 of the X-ray tube. The other electrode is connected to the anode of the rectifying tube 9 and to a current-supply conductor 15.

The condensers and rectifiers serve to increase the voltage applied so that the supply voltage need be only part of the voltage of the tube.

The current transformer 12 has a primary winding 16 which is energized from the exterior with a low voltage, and two secondary windings 17 and 18 which are insulated for high tension relatively to one another and to the winding 16. The incandescent cathode of the rectifying tube 8 is energized by the winding 17 and the incandescent cathode of the rectifying tube 9 is energized by the winding 18.

The current transformer 13 has a primary winding 19 which is energized from the exterior with a low voltage, and a secondary winding 20 which is insulated for high tension relatively to the winding 18. The incandescent cathode of the X-ray tube is energized by the winding 20. If it is not necessary to control the heating voltage of the X-ray tube, a single heating-current transformer having one primary winding and three secondary windings suffices.

The heating-current transformers 12 and 13 are arranged in projecting caps 23 and 24 which also serve as journals to suspend the whole in a rotary manner from a bow 25 by means of which the apparatus may be fastened to a support.

The current-supply conductors 14 and 15 are provided with insulation surrounded by a conductive coating. The latter is connected to the tank 22 and is grounded during the use of the apparatus.

The X-ray tube is of the type in which the heat which is developed in the anode during the use is absorbed by the metal part of the wall. Due to this metal part being in good heat-conductive contact with the metal part 5, the heat is directly taken over by this body and given off to the plate 21. So far as the heat is not already given off by this cover to the surrounding air it is further dissipated in the wall of the housing. Due to the large heated surface that is available the temperature of all parts remains low. Only the anode of the X-ray tube may attain a comparatively high temperature, for example 500°

C., but all the parts with which the insulating liquid makes contact are but slightly heated. This is very advantageous for the preservation of the quality of the liquid as an insulator and makes it possible for the apparatus to have smaller dimensions than it would be the case if the heat would have to be carried off through the liquid. It is true that a small loss of heat from the heating-current transformers and further components is absorbed by the liquid but it is too slight to cause a considerable increase of the temperature of the liquid.

An apparatus such as described for a continuous power of 100 watts may have a total length of 50 cm. (30 cm. without the projecting caps 23 and 24), a height of 25 cm. and a width of 12 cm.

The lead layer 2 surrounding the metal part of the X-ray tube promotes a good heat-conduction between the tube and the body 5 since the soft metal may be easily forced into the irregularities of the surfaces of the metal bodies.

If the side-walls of the housing 22 or one of these walls are not of too thick metal they can slightly curve to the exterior in the case of expansion of the liquid, resulting in a sufficient increase of volume to permit the expansion of the liquid which is but slight due to the highly moderate heating.

What we claim is:

1. In an X-ray apparatus, an X-ray tube comprising an evacuated envelope, a cathode and an anode within said envelope, said envelope comprising a metal wall portion electrically insulated from and extending beyond the ends of the anode and absorbing substantially all of the heat generated thereby, a metal container enclosing the X-ray tube, an insulating fluid in said container and metallic heat transmitting means directly conducting substantially all of the heat absorbed by said wall portion to said container.

2. In an X-ray apparatus, an X-ray tube comprising an evacuated envelope, a cathode and an anode within said envelope, said envelope comprising a metal wall portion electrically insulated from and extending beyond the ends of the anode and absorbing substantially all of the heat generated thereby, a metal container enclosing the X-ray tube, an insulating fluid in said container, means securing said tube to a wall of said container, said means directly conducting to said container substantially all of the heat absorbed by said wall portion and comprising a metal member in thermal contact with the metal portion of the envelope and the wall of said container, said member having engaging surfaces conforming to the surfaces of said metal portion of said envelope and to said container wall.

3. In an X-ray apparatus, an X-ray tube comprising an evacuated envelope, a cathode and an anode within said envelope, said envelope comprising a metal wall portion electrically insulated from and extending beyond the ends of the anode and absorbing substantially all of the heat generated thereby, a metal container enclosing the X-ray tube, an insulating fluid in said container, means securing said tube to a wall of said container and directly conducting substantially all of the heat absorbed by said wall portion to said container, said means comprising a metal saddle member secured to said container wall and to the metal portion of said envelope

and a soft metal layer interposed between said saddle member and the metal portion of said envelope.

4. In an X-ray apparatus, an X-ray tube comprising an evacuated envelope, a cathode and an anode within said envelope, said envelope comprising a metal wall portion electrically insulated from and extending beyond the ends of the anode and absorbing substantially all of the heat generated thereby, a metal container enclosing the X-ray tube, an insulating fluid in said container, means securing said tube to a wall of said container and directly conducting substantially all of the heat absorbed by said wall portion to said container, said means comprising a metal saddle member secured to said container wall and to the metal portion of said envelope and a layer of lead metal interposed between said saddle member and the metal portion of said envelope.

5. In an X-ray apparatus, an X-ray tube comprising an evacuated envelope, a cathode and an anode within said envelope, said envelope comprising a metal wall portion electrically insulated from and extending beyond the ends of the anode and absorbing substantially all of the heat generated thereby, a metal container enclosing the X-ray tube, an insulating fluid substantially filling said container, means directly conducting substantially all of the heat absorbed by said wall portion to said container, and means to permit heat expansion of said fluid, said means comprising a concave deformable resilient wall portion of said container.

6. In an X-ray apparatus, an X-ray tube comprising an evacuated envelope, a cathode and an anode within said envelope, said envelope comprising a metal wall portion electrically insulated from and extending beyond the ends of the anode and absorbing substantially all of the heat generated thereby, a metal container enclosing the X-ray tube, an insulating fluid in said container, means securing said tube to a wall of said container and directly conducting substantially all of the heat absorbed by said wall portion to said container, said means comprising a metal saddle member secured to said container wall and engaging the metal portion of said envelope and a metal clip member embracing the metal portion of said envelope and securing said tube to said saddle member.

7. In an X-ray apparatus, an X-ray tube comprising an evacuated envelope, a cathode and an anode within said envelope, said envelope comprising a metal wall portion electrically insulated from and extending beyond the ends of the anode and absorbing substantially all of the heat generated thereby, a metal container enclosing the X-ray tube, an insulating fluid in said container, means securing said tube to a wall of said container and directly conducting substantially all of the heat absorbed by said wall portion to said container, said means comprising a metal saddle member secured to said container wall and engaging the metal portion of said envelope and a metal clip member embracing the metal portion of said envelope and securing said tube to said saddle member, and a layer of soft metal surrounding the metal portion of said envelope and in contact with said clip member and said saddle member.
